CLAIM

The ornamental design for a digital stereo condenser microphone for an electronic device, as shown and described.

DESCRIPTION

FIG. 1 is a front and bottom perspective view of a digital stereo condenser microphone for an electronic device showing my new design;

FIG. 2 is a rear and top perspective of the digital stereo condenser microphone for an electronic device;

FIG. 3 is a front view of the digital stereo condenser microphone for an electronic device;

FIG. 4 is a rear view of the digital stereo condenser microphone for an electronic device;

FIG. 5 is a left side view of the digital stereo condenser microphone for an electronic device;

FIG. 6 is a right side view of the digital stereo condenser microphone for an electronic device;

FIG. 7 is a top view of the digital stereo condenser microphone for an electronic device;

FIG. 8 is a bottom view of the digital stereo condenser microphone for an electronic device; and,

FIG. 9 is an enlarged view of an encircled portion of the digital stereo condenser microphone for an electronic device labeled 9 shown in FIG. 7.

The broken lines in the drawings depict portions of the digital stereo condenser microphone for an electronic device that form no part of the claimed design, and the evenly-dashed broken lines shown in the drawings encircling portions of the digital stereo condenser microphone for an electronic device illustrated in enlargements form no part of the claimed design.

1 Claim, 9 Drawing Sheets
